Fred W. Hatch.

UNITED STATES PATENT OFFICE.

FRED W. HATCH, OF BARRONETT, WISCONSIN.

FUNNEL.

1,311,393.

Specification of Letters Patent. Patented July 29, 1919.

Application filed May 26, 1917. Serial No. 171,248.

To all whom it may concern:

Be it known that I, FRED W. HATCH, a citizen of the United States, residing at Barronett, in the county of Barron and State of Wisconsin, have invented certain new and useful Improvements in Funnels, of which the following is a specification.

This invention relates to new and useful improvements in funnels and the principal object of the invention is to provide a device of this character with means for preventing the receptacle being filled from being filled too full.

Another object of the invention is to provide means for preventing the liquid from flowing from the funnel after the liquid in the receptacle reaches a certain point therein.

A further object of my invention is to provide a device of the above mentioned character including means whereby liquid in the body part of the funnel is prevented from forcing the valve off of its seat when a receptacle to which the funnel is applied is filled, and at the same time provides a guide for the proper placement of the valve upon its seat.

Another object of the invention is to provide a device of this character, which is simple and durable in construction, reliable and efficient in operation and one which can be manufactured and placed upon the market at a minimum cost.

The invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings, wherein like characters denote like or corresponding parts throughout the several views, and in which:

Figure 1 is a vertical section of my invention inserted in a receptacle, and

Fig. 2 is a transverse section of the invention taken on the line 2—2 of Fig. 1.

In the drawings 1 indicates the funnel of the ordinary form and having a spout 2 which is to enter the receptacle indicated at 3. In carrying out my invention I place a tube 4 in the funnel and this tube extends from the bottom of the spout to the top of the funnel. I may solder this tube to the spout to hold it in place, or I may form the tube by placing a curved partition in the

spout and soldering its edges to the walls of this spout to form the lower end of the tube.

A second tube 5 is eccentrically placed in the funnel at the top of the spout and extends up into the body part of the funnel. This tube 5 forms an outlet passage from the funnel to the spout and liquid entering the spout must pass through this tube. As will be evident, this tube prevents liquid in the funnel from pushing under the ball valve 7 to unseat the same after the receptacle 3 to which the funnel has been applied has been filled. The spaces between the tubes 4 and 5 and the inner walls of the body of the funnel are occupied by plates 5' of suitable shape so that any liquid passed from the funnel must pass through the tube 5.

I arranged a valve seat 6 consisting of a ring in this tube to receive a ball valve 7 which is carried by a rod 8, said rod extending up to the top of the funnel and being pivotally connected to one end of a lever 9, pivoted intermediate its ends to the top of the tube 4. The other end of this lever is pivoted to a rod 10, extending into the tube 4 and being connected at its lower end with a float 11, made of cork or any other suitable material. The tube 5 also forms a guide for the ball valve for properly placing the same upon its seat when the rod 8 swings outwardly upon its pivotal connection with the lever 9. The tube 4 is provided with projections 12 for limiting the downward movement of the said float.

The rod 10 is made sufficiently heavy to counter balance the weight of the valve 7 and its rod so as to normally keep the valve open. The float is so located in the spout that it will lie below the top of the receptacle to be filled when the funnel is placed therein. Thus when the level of the fluid in the receptacle reaches a certain point therein the float will be raised thereby and the rod 10 will raise the lever 9 so as to force down the rod 8, thus pressing the valve upon its seat and preventing the liquid from flowing from the funnel into the receptacle and causing the same to over flow.

When the valve 7 is seated and the liquid is caught in the funnel the weight of this liquid will prevent the valve from leaving its seat when the funnel is removed from the receptacle and the cork float is removed from the action of the liquid in the receptacle. The liquid in the funnel may then

be released by pulling up on the rod 8 to raise the valve or the liquid may be poured from the mouth of the funnel.

It is thought from the foregoing that the 5 advantages and novel features of my invention will be readily apparent.

I desire it to be understood that I may make slight changes in the construction and in the combination and arrangement of the 10 several parts, provided that such changes fall within the scope of the appended claims.

I claim as my invention:

1. A funnel comprising a body portion and a spout, a lever pivoted adjacent the 15 top of said body portion, a rod pivoted to each end of said lever and depending therefrom, a float secured to one rod and a ball valve secured to the other, an imperforate tube having open ends, being secured to the 20 top of said spout and extending up into the body portion and arranged eccentrically of said spout, plates of suitable shape closing the space between the tube and the inner walls of said body portion whereby all 25 liquid passing through the spout must pass

through said tube, and a ring secured to the inner periphery of said tube a substantial distance from the top thereof to form a valve seat, whereby liquid being poured into the funnel is prevented from dislocating 30 the ball valve when the receptacle to which the funnel is applied, is filled.

2. A funnel comprising a body portion and a spout, a vertical imperforate tube extending through said spout from the bottom 35 thereof to the top of the body portion of said funnel and arranged eccentrically of the spout, a valve seat in said spout, a ball valve for coöperation with said valve seat, a float in said tube, a lever pivoted to the top edge of said tube, and vertical rods connecting the free ends of said lever to the float and valve.

In testimony whereof I affix my signature in presence of two witnesses.

FRED W. HATCH.
